PAINT REMOVING TOOL

Harold Christopherson, Bronx, N. Y.

Application July 15, 1942, Serial No. 451,085

2 Claims. (Cl. 30—277)

My invention relates to the removal of paint, particularly on the hulls of ships, and has among its objects and advantages the provision of an improved paint removing tool.

In the accompanying drawing:

Figure 1 is an end view of a tool in accordance with my invention;

Figure 2 is a sectional view along the line 2—2 of Figure 1;

Figure 3 is a sectional view taken along the line 3—3 of Figure 2; and

Figure 4 is a sectional view of a modified form of the invention.

In the embodiment selected for illustration, I make use of a head 10 having a shank 12 for connection with a vibrating tool (not shown). To the head 10 is connected a casing 14 by screws 16, which casing is provided with an end wall 18 having openings 20 for loosely receiving the shanks 22 of paint removing tools 24 having paint cutting blades 26.

Figures 1, 2 and 3 illustrate five tools 24, and each shank 22 is loosely positioned in a recess 28 in the head 10. The shanks 22 are arranged in parallel relationship and are free to rotate about their longitudinal axes while in operation.

In removing paint, the head 10 is connected with a suitable vibrating tool and the blades 26 are brought into edge engagement with the painted surface. The vibrating tool is then set in motion for transmitting such vibrations to the head 10 and the tools 24. Such vibrations cause the blades to hammer or cut the paint and rotate about the axes of the shanks 22 to cut the paint from the hull.

In moving the tool from place to place, it is desirable to latch the tools 24 against accidental dropping from the head and the housing. Such means comprises a cable 30 having one end provided with a loop 32 encircling the shank 22 of the central tool 24. The cable is then wound over the remaining shanks 22 and connected at 34 with one end of a lever 36 pivotally connected at 38 with the end wall 18. The lever 36 is bent so that the tension of the cable 30 holds the lever firmly against one of the shanks 22 when the lever is pivoted to the position of Figure 1 for

firmly clamping the tools in position. A slight pivotal movement of the lever in a counter-clockwise direction loosens the cable 30 to free the tools.

5 Figure 4 illustrates a slightly different form of invention wherein the tool shanks 22 are loosely supported in tubes 40 fixedly connecting an end plate 42 with the head 44 corresponding to the head 10. In other respects the tool structure of Figure 4 is identical with that illustrated in Figures 1 through 3.

The tool embodies a plurality of paint cutting blades which perform an efficient paint cutting function when vibrated, with the paint cutting tools loosely mounted so as to rotate freely under the influence of the vibratory motion. Thus the tool is designed to span a relatively large area to facilitate removal of the paint in an expeditious manner.

Without further elaboration, the foregoing will so fully illustrate my invention, that others may, by applying current knowledge, readily adapt the same for use under various conditions of service.

I claim:

1. A paint cutting tool comprising a vibratory head, tubes fixedly connected with said head, a plate fixedly connected with said tubes, paint cutting tools having shanks loosely supported in said tubes, and flexible means coacting with said tools and said plate to frictionally secure the tools against accidental displacement.

2. A paint removing tool comprising a head adapted for connection with a vibrator, said head being provided with a housing having an end wall provided with openings, said head having recesses coaxially positioned with said openings, paint cutting tools having blades and shanks loosely supported in said openings and said recesses for unrestrained rotation about the axes of the shanks, a cable attached at one end to one of said shanks and wound about the other shanks, and a lever pivotally connected with said end wall and connected with the other end of the cable for placing the cable under tension to frictionally hold the tools against accidental displacement.

HAROLD CHRISTOPHERSON.
